(57) **CLAIM**

The ornamental design for a front portion of a motor vehicle, toy replica, and/or other replica as shown and described.

DESCRIPTION

FIG. 1 is a top, front and right side perspective view of a front portion of a motor vehicle, toy replica, and/or other replica according to the design;

FIG. 2 is a rear and right perspective view thereof;

FIG. 3 is a front elevation view thereof;

FIG. 4 is a right side elevation view thereof;

FIG. 5 is a left side elevation view thereof; and,

FIG. 6 is a top plan view thereof.

The broken lines in the drawings illustrate environmental subject matter only and form no part of the claimed design.

1 Claim, 6 Drawing Sheets
